UNITED STATES PATENT OFFICE

ROLLAND G. WILLIAMS, OF BRANFORD, CONNECTICUT, ASSIGNOR TO MALLEABLE IRON FITTINGS COMPANY, OF BRANFORD, CONNECTICUT, A CORPORATION OF CONNECTICUT

GAIN FIXTURE FOR POLES

Application filed May 21, 1929. Serial No. 364,858.

This invention relates to gain fixtures for poles and has for its object to secure the fixture in a stable manner to the pole without the use of any bolts extending entirely through the pole and without breaking down the fiber of the pole, the body portion of the fixture being so formed as to provide a ventilating air space between the pole and said body, as well as an air space extending entirely through said body, so that the cross-arm supported by the latter will be exposed to the air throughout the major portion of its rear face.

A further object is to secure the cross-arm to the fixture without the use of any bolts extending into or through the pole.

In the accompanying drawing

Figure 1 is an elevation showing the fixture secured to the pole and with the cross-arm bolted to the fixture.

Figure 2 is a section at the line 2—2 of Figure 1.

Figure 3 is a plan view, of the structure shown at Figure 1, and

Figure 4 is a detail rear elevation of the fixture itself.

Similar numerals of reference denote like parts in the several figures of the drawing.

Heretofore metal gain fixtures have been secured to a pole, but they have been equipped with chisel shaped flanges that have been driven into the pole by the process of securing the fixture thereto thus breaking down the fiber of the pole thereby readily admitting moisture and eventually causing the pole to rot so as to bring about the loosening of the fixture.

Also the cross-arm has been secured by means of a bolt that extended entirely through the pole, and as this bolt was frequently driven through a comparatively small opening into the pole so as to secure tightness, the consequence has been that the pole would start to split which splitting would be increased as the strain brought to bear on the fixture during heavy storms would cause swaying of wires possibly heavily laden with ice.

In the present improvement the cross arm

is secured to the fixture itself and the pole is not penetrated.

1 is the pole and 2 the main body portion of the fixture which has a plurality of perforations 3 extending therethrough and taking up the greater area of this body portion.

4 are spaced elongated ledges which extend from the front of the fixture, 5 is a leg extending from the body portion 2 at the middle top portion thereof and 6 are spaced legs 60 extending from the lower portion of said body.

7 is a lag screw driven into the pole through the leg 5 and 8 are lag screws likewise driven into the pole through the legs 6 these lag screws affording means for securing the fixture to the pole at three triangularly disposed points, thus insuring stability.

In the rear face of the body portion 2 is a countersunk rectangular recess 9, for the purpose presently to be explained.

10 is a cross-arm positioned between the ledges and secured to the fixture by means of a bolt 11 whose head 12 is housed within the recess 9, a nut 13 being driven on the front end of the bolt against a washer 14 placed against the front face of the cross-arm.

The rear face of the body portion 2 is spaced from the pole 1 as seen at 15, so that it will be clear that the only point of contact 80 that the fixture has with the pole is through the medium of the legs 5 and 6, while the body portion itself, owing to the plurality of openings 3, affords free access of air to the rear face of the cross-arm 10 thus preventing the sweating and consequently rotting of the latter due to the presence of moisture.

There is no breaking down of the fiber of the pole, since the holes for the lag screws are 90 clean cut, and therefore the likelihood of any rotting of the pole due to the securement of the fixture is reduced to a minimum.

It will, of course, be obvious that the position of the fixture on the pole may be reversed, and in this instance the legs 6 would be at the top of the fixture while the leg 5 would be at the bottom.

What is claimed is:

The herein-described gain fixture for poles 100

- comprising a main body portion having an angular recess at the center of its rear face and a plurality of air openings extending through its back from front to rear, a single leg extending from the top of said portion and midway thereof, a pair of legs extending from the lower ends of said portion, said legs having feet that are concaved to closely contact the pole, horizontal spaced ledges formed at the front of said body portion and adapted to house a cross-arm, lag screws driven through said legs into the pole, said body portion being spaced from the pole whereby an air space is provided between said pole and portion, a cross-arm positioned between said ledges, a bolt having an angular head that is housed within said recess, said bolt extending through said cross-arm, and a nut driven on the end of said bolt against said cross-arm.
- 20 In testimony whereof I affix my signature hereto.

ROLLAND G. WILLIAMS.
